UNITED STATES PATENT OFFICE.

ALWILL URBAHN, OF PATERSON, NEW JERSEY, ASSIGNOR OF ONE-HALF
TO ABRAHAM G. JENNINGS, OF BROOKLYN, NEW YORK.

WOVEN FABRIC AND LOOM FOR WEAVING THE SAME.

SPECIFICATION forming part of Letters Patent No. 289,781, dated December 4, 1883.

Application filed December 10, 1882. (Specimens.)

To all whom it may concern:

Be it known that I, ALWILL URBAHN, of Paterson, in the county of Passaic and State of New Jersey, have invented an Improved 5 Woven Fabric and Loom for Weaving the Same, of which the following is a specification.

Figure 1 is a sectional elevation of the loom on which my improved fabric is produced. 10 Fig. 2 is a top view of the harness and reeds of said loom; Fig. 3, a front view of the ground warp harness; Figs. 4 and 5, detail face and sectional views, respectively, of part of the harness, and Fig. 6 a face view of part of the 15 reed; Fig. 7, a vertical cross-section thereof; Figs. 8, 9, 10, 11, and 12, face views of my new fabric.

This invention consists, first, of a new woven fabric; and, secondly, of a new construction 20 of loom for weaving such fabric. The fabric is produced by interweaving shuttle and crossed ground warp threads, to form a foundation fabric, and securing thereto upper ornamental cords, which are held to the body of the fabric 25 by shuttle-threads, which pass over the ornamental cords, the ground warp threads being all beneath the same. The loom is provided with heddle-frames having perforated needle-like heddles, through which the ground warp 30 threads, and also the figure-cords, are drawn, in combination with a new reed, which is made of doubly-looped pillars, all as hereinafter more fully described.

In the drawings, the letter A represents the 35 frame of the loom. B is the beam from which the ground warp threads for the foundation fabric are taken. These warp-threads are marked *a* and *b* in Fig. 1, and are carried through the heddles or needles of the heddle- 40 frames C and D. Each of these heddle-frames has a series of needle-like heddles, *d*, as more clearly shown in Figs. 4 and 5, the said needles or heddles *d* projecting downward in one of the heddle-frames, C, and upward in the other 45 heddle-frame, D, as shown in Figs. 1 and 3. The needles *d* of the heddle-frames have holes near their free ends, and through these holes the ground warp threads are drawn. The heddle-frame C, which has the downwardly-projecting needles, is guided vertically in a

frame, E, which is supported on pivoted posts F, as indicated in Fig. 3, or otherwise arranged, so that said frame E can be moved laterally by hand or by machinery, and with it the said heddle-frame C, while at the same time the heddle-frame C can be moved vertically in the frame E by the usual treadle and harness connection. The other heddle-frame, D, which has the upwardly-projecting needles, is guided in a fixed frame, G, and only capable of up-and-down motion; yet this frame G, if desired, may also be made laterally movable. The motion to be imparted to these heddle-frames C D is such, in order to produce the foundation fabric which I desire, that after 55 the shed is once open, as shown in Fig. 1, and after the shuttle H has carried a shuttle-thread through this shed, the heddle-frame C will be raised, and after the lower ends of its needles or heddles *d* are above the upper ends of the 60 needles in the heddle-frame D, the heddle-frame C will be moved laterally, so as to carry each one of its needles over the vertical plane of one of the projecting needles of the heddle-frame D, and then the heddle-frame C will be 65 lowered again, so that in the shed, whenever the shuttle is thrown, the warp-threads *a*, that are carried by the heddle-frame D, will always be above the warp-threads *b*; but before receiving every new shuttle-thread the 70 two adjoining warp-threads *a b* are made to cross one another by the above-described motion of the heddle-frame C, thereby producing the effect which is clearly indicated in Fig. 12, where *a b* are the crossed ground 75 warp threads and *i* the shuttle-threads. The ground warp threads *a b*, after having passed through the heddle-frames C D, are passed through the lower pillars, *e*, of the lower reed, I, and after having received the shuttle- 80 threads and the figure-threads the whole fabric is wound upon the beam J, or carried from said beam to a suitable other beam, L. The lower reed, I, is fastened and moved in the manner customary in existing looms with reference to the moving and connection of the 85 reed and batten, a handle being shown for that purpose in Fig. 1 of the drawings. The figure cords or threads for ornamenting the 90 face of the fabric are taken from a beam, M, 95 100

and carried in suitable strands, *f f*, through one or more heddle-frames, *N N*, and then between the downwardly-projecting pillars *g* of the upper reed, *P*. Each of the heddle-frames *N* has downwardly-projecting needles *d*, like the needles of the heddle-frames *C* and *D*, and the figure-cords *f* are drawn through the holes that are near the free ends of these needles. The upper reed, *P*, is suspended from the batten-frame by cords, as shown in Fig. 1, or otherwise, in such a manner that it is capable of slight lateral motion, which may be imparted to it by hand.

The pillars of the two reeds *I* and *P* are made, as more clearly shown in Figs. 6 and 7, as follows. Those of the lower reed, *I*, are upwardly-projecting looped wires, resembling hair-pins, and the warp-threads *a b* pass through these closed loops, so that they cannot escape from them. The pillars *g* of the upper reed, *P*, are looped wires of exactly the same character as those of the lower reed, excepting that they project downward; but the figure-threads or ornamenting-cords *f*, instead of being passed through these pillars, as do the ground warp threads, are passed through the spaces between the looped pillars, as indicated in Fig. 6. This arrangement enables me, by shifting the upper suspended reed, *P*, laterally, to carry any one of the figure-threads over the space between any two pairs of ground warp threads, and then, by lowering the corresponding heddle-frame, *N*, to bring such figure-thread into the lower part of the shed, wherever it may be desired to have it tied to the ground fabric by the shuttle-thread. By this arrangement I am enabled to produce on the loom, without further guidance, the ornamentation in any desired form, as is indicated by Figs. 8, 9, 10, and 11—that is to say, all the figure-threads can be carried along simultaneously in zigzag order and tied down by the shuttle-threads *i*, as in Fig. 9, in which case only one heddle-frame, *N*, is necessary; or when two such heddle-frames are employed the effect shown in Figs. 8, 10, and 11 can be produced. To this end the reed *P* is moved laterally, whenever required, and thereupon only one of the heddle-frames *N* is lowered, and its figure-threads are tied to the ground fabric. Then the frame *P* is again moved laterally, and then the next frame *N* is brought down. This will produce the diamond-like design shown in Fig. 10.

When, between the lateral motions of the reed *P*, the heddle-frames *N N* are raised and

lowered at proper intervals, the figure-threads will be placed in straight rows between zig-zag bends, as in Figs. 8 and 11. It is essential in this connection that the heddle-frames *N* should partake of the lateral motion which is from time to time imparted to the reed *P*, either by hand or otherwise. To this end the reed *P* is provided with arms *h*, as shown in Fig. 2, that extend backward and straddle the ends of the heddle-frames *N N*, so that whenever the reed *P* is moved laterally the heddle-frames *N N* will move laterally to the same extent. The lower reed, *I*, has no lateral motion, but is moved backward and forward in the usual manner of operating reeds or battens. The upper reed-loops, *g*, need not be open loops, but may be closed plates or arms, as the spaces between them are only utilized. Such solid arms are therefore equivalents of the upper loop, *g*.

The heddle-frames may be connected with treadles *C'*, and in part suspended from upper beams or levers, *D'*, in the customary manner, and as common in ordinary loom-harness, such connections being clearly shown in Fig. 1.

I claim—

1. As a new article of manufacture, a fabric consisting of crossing ground warp threads *a b*, shuttle-threads *i*, which shuttle-threads are held throughout below the warp-thread *a* and figure-threads *f*, which are held by the shuttle-threads only, substantially as described.

2. The reed *I*, having upwardly-projecting open warp-guiding loops *e*, combined with and placed vertically below the upper reed, *P*, having downwardly-projecting figure-thread guiding-loops *g*, and with means, substantially as described, for supporting said reed *I* and moving it backward and forward in the loom as a batten, and for supporting said reed *P* and moving it laterally, all as set forth.

3. The combination of the heddle-frames *C D N*, having the perforated needle-like heddles *d*, with the reeds *I P*, having looped pillars *e g*, and with mechanism for supporting and moving said heddle-frames and reeds, substantially as described.

4. The combination of the reed *P* with the arms *h h* and heddle-frames *N N*, and with means for supporting and operating the same, substantially as and for the purpose herein shown and described.

ALWILL URBAHN.
